INTERIOR BUILDING CONSTRUCTION

Filed May 1, 1928

UNITED STATES PATENT OFFICE

CLARENCE H. COLLINGS, OF CLEVELAND HEIGHTS, OHIO

INTERIOR BUILDING CONSTRUCTION

Application filed May 1, 1928. Serial No. 274,264.

This invention relates to interior building construction and has for its object the provision of a simple, light, and inexpensive partition structure. In connection with domestic 5 bath rooms, public lavatories, barber shops, hospitals, beauty parlors, etc. it often becomes desirable to erect a partition as for a shower-bath, toilet, compartment, booth, etc. To maintain sanitary condition it is necessary 10 that the same be vitreous or ceramic which practically requires either marble which is expensive or tile, which with the previous types of construction has entailed such thickness of wall as to waste valuable space.

15 The objects of my inventions are the provision of an improvement in tile construction whereby the cheapness of tile can be combined with an economy of space approaching that obtainable with marble; the provision of new 20 and useful expedients for reinforcing and supporting and adjusting a tile wall; the provision of a new, improved, and simplified, reinforced tile construction which shall require a minimum number of special shapes or other 25 special parts; while further objects and advantages of the invention will become apparent as the description proceeds.

In the drawings accompanying and forming a part of this application Fig. 1 is a perspective view of a part of a domestic bathroom comprising a showerbath compartment containing my improvements; Fig. 2 is a horizontal sectional view on the line 2—2 of Fig. 1; Fig. 3 is a detail view of part of the top construction of the partition shown in Fig. 1; Fig. 4 is a sectional view corresponding to the lines 4—4 of Figs. 1 and 3; Fig. 5 is a sectional view taken through the upper corner of the partition shown in Fig. 1; Fig. 6 is a horizontal sectional view taken on the line 6—6 of Fig. 1; and Fig. 7 is a perspective view of the top corner reinforcement of the partition shown in Fig. 1.

I have shown a chamber comprising floor tiles 1 and wall tiles 2—2 bedded on a cementitious layer 3 applied to the base structure 4. In the walls I embed metal plates 5 (Figs. 3 and 4) having threaded sockets in which are screwed the ends of the horizontal metal rods 6 which define the course of the

partition. It is oftentimes sufficient if these rods are located at the top of the partition only, but I have here shown same at both top and bottom.

At their meeting ends these rods are 55 screwed into the hollow sockets 7 of terminal members which are formed with overlapping eye-pieces 8—8 apertured for the reception of the vertical reinforcing rod 9. The sockets 7 and the corresponding ends of the rods 6 are preferably formed with left-hand threads as shown in Fig. 5, while the opposite ends of said rods and the plates 5 are formed with right-hand threads, so that by screwing the rods respectively back and forth it is 60 possible to bring the upright rod 9 strictly vertical. When no bottom rods are used, the lower end of the rod 9 is set in a socket 10 formed in the floor, and this socket can still be used with the rods, if desired. 65

Strung on the rod 9 are the vertically recessed or apertured corner blocks 12, which are made of suitable ceramic material and of any external shape which pleases the fancy. I have here shown these blocks as provided at 75 one corner with a metal strip 13 which comprises both a strike 14 for the door stile 15 and a stop portion 16 cooperating with the opposed shoulder 17 on the block to hold in place the glass panel 18. It is, of course, 80 necessary to apply the blocks 12 to the rod 9 prior to the eye-pieces 8—8; and it improves the construction to surround the rods 9 with cement if desired although this is not always necessary. 85

After this corner has been erected as heretofore described, the horizontal rods 6 are covered by other tiles 20, each of which is formed along its upper edge with an undercut longitudinal recess 21. The width of this recess at the mouth is necessarily somewhat greater than the diameter of the rod 6, and its width at a point inside the mouth is increased somewhat. These recesses are supplied with a plastic, easily-flowing, cement 95 just prior to the application of the blocks to the rod so that the cement flows about and snugly embraces the rod, whereupon the blocks are propped in place until the cement hardens after which they are permanently 100

held. The bottoms of the partitions may be made of the same kind of blocks illustrated at 20 although I prefer to use higher blocks 24. When the horizontal rods 6 are used these blocks are also grooved in the same manner as the blocks 20 and it will be noted that the employment of the rods 6—6 at the bottom dispenses with the necessity of grooving the floor.

10 The remaining margins of the partitions are built up of vertical blocks 25, here shown as identical with the blocks 20 and likewise having grooves 21 in their concealed edges. In the present embodiment I have shown the 15 wall-tiles 2 as spaced apart to define a channel or groove 26 in which these upright blocks are laid and with this construction the grooves 21 are comparatively functionless. However, it is within my invention to employ a vertical rod at this point, similar to the rod 6—6 at floor and roof, in which event the 20 partition is held rigid without need for channelling the side walls.

25 The blocks 12, 20, 24, and 25 cooperate to define a rectangular frame for the reception of the glass panel 18 the faces of the blocks being suitably grooved or shouldered as shown at 28 and 17 to receive the margins of that panel. When a door is used as herein 30 shown it preferably comprises metal stiles 15 and a glass panel 29. The glass or other paneling material used for this purpose may be either transparent, translucent, or opaque, depending upon the purpose in view, as for 35 telephone-booths or bathing-compartments, etc.

40 In the foregoing description and illustration I have, for purposes of simplicity, restricted the numbers and shapes of the different blocks and tiles, but it will be obvious that many changes in these shapes and designs can be made without departing from my inventive idea, and many other variations in detail wherefore I do not limit myself in 45 any wise except as specifically recited in my several claims which I desire may be construed broadly each independent of limitations contained in other claims.

Having thus described my invention what 50 I claim is:

55 1. In tile construction, a rectangular frame work of metal rods, means for adjusting the sides of said frame, and tiles having recesses receiving and concealing the frame members and held in place thereby, the recesses in certain of said tiles consisting of under-cut channels adjacent to one edge, and a cementitious substance located in said channels and embracing the frame member therein.

60 2. In tile construction the combination with a horizontal rod of a tile having in its upper face an undercut recess, the mouth of which is at least as wide as said rod and the body of which is wider than said rod, and 65 cement in said recess surrounding said rod.

3. In tile construction, a reinforcing frame comprising three metal rods diverging from a single point, each rod perpendicular to each other of said rods, terminal pieces screwed on two of said rods, each of said terminal pieces having a flattened extension formed with an aperture through which the third rod extends, means for anchoring the other ends of said three rods, and tiles having recesses receiving and concealing said rods and terminal pieces and held in place thereby, the portion of said recess not filled by the rods having mortar therein.

4. In tile construction, the combination with a wall and a floor of a partition comprising a plurality of metal rods located at right angles to each other, terminal pieces screwed to certain rods and having apertures at right angles thereto slidably receiving another rod, socket provisions for the opposite ends of such rods, tiles having recesses receiving and concealing said rods and pieces and held in place thereby, and panel members 85 framed by said tiles, the portion of said recess not filled by the rods having mortar 90 therein.

5. In tile construction, in combination, a panel of vitreous material, a framework of vitreous blocks embracing the same, said blocks having shoulders engaging said panel and recesses parallel to the adjacent edge of said panel and spaced therefrom, metal reinforcing rods in said recesses, means securing said rods to a wall, and cement embracing 95 said rods in said recesses.

6. In tile construction, the combination with the walls of a chamber of a chamber of metal rods parallel to said walls, means for anchoring the ends of said rods, vitreous blocks, each having panel receiving provisions at one side and undercut recesses opening through another side, said recesses covering said rods, and cement filling the space between the rods and the sides of said recesses.

7. In tile construction, the combination with the intersecting floor and walls of a chamber, of an upright rod spaced from both walls and engaging the floor, a pair of horizontal rods secured to said walls and converging toward said first rod, apertured end pieces secured to said horizontal rods, the apertures receiving said first rod, a vertical row of recessed vitreous blocks strung on said first rod, and a horizontal row of recessed vitreous 115 blocks strung along each of said horizontal rods, the recesses of said last named blocks opening through a concealed face thereof and being filled with cement around the respective rods.

8. In tile construction, the combination with the intersecting floor and walls of a chamber, of an upright rod spaced from both walls and supported by the floor, a threaded socket member secured to each wall, a thread- 120 125 130

ed socket member secured to said upright rod opposite each of said first socket members, a horizontal rod having its ends threaded into each pair of sockets, certain of the threads being right and left to enable truing up the 5 angles between the rods, panels in the planes defined by said rods, and marginal blocks of vitreous material engaging the edges of said panels, said block having recesses for said rods and concealing said rods, and cement fillings in said recesses around the rods.

10 In testimony whereof I hereunto affix my signature.

CLARENCE H. COLLINGS.
